Inventor:

Riley Burdett.

UNITED STATES PATENT OFFICE.

RILEY BURDETT, OF ERIE, PENNSYLVANIA.

IMPROVEMENT IN ORGAN REED-BOARDS.

Specification forming part of Letters Patent No. **155,178**, dated September 22, 1874; application filed June 13, 1874.

To all whom it may concern:

Be it known that I, RILEY BURDETT, of Erie, in the county of Erie and State of Pennsylvania, have invented an Improvement in Reed-Organs, of which the following is a specification:

This device is illustrated in the accompanying drawing, which is a transverse sectional view of it.

The object of my invention is to strengthen and purify the reed tone.

A shows the foundation-board. B shows the socket-board. C shows what I designate a cushion air-chamber.

My device differs from the ordinary reed-boards in having a continuous air-chamber or continuous air-chambers immediately over the reed-cells, and communicating therewith, and cushioning the air, so to speak, as it enters

the reed-cell to vibrate the reed, so as to produce a greatly improved and strengthened tone over that tone from a reed-cell as ordinarily constructed.

I am aware that the reed-cell has been extended upward and rearward, as in Goodman's patent, No. 109,003, and also of the construction of W. J. Kent, No. 144,549. These are not my inventions, and their effects are not like the effect of mine.

What I claim is—

A reed-board provided with the celis B, and having the chambered recesses or cells C arranged relatively thereto as described and shown.

RILEY BURDETT.
